UNITED STATES PATENT OFFICE.

ALFRED C. GILBERT, OF HAMDEN, CONNECTICUT, ASSIGNOR, BY MESNE ASSIGNMENTS, TO THE A. C. GILBERT COMPANY, OF NEW HAVEN, CONNECTICUT, A CORPORATION OF MARYLAND.

DESIGN FOR A CASING FOR FRUIT-JUICE EXTRACTOR.

Application filed March 24, 1928. Serial No. 25,987. Term of patent 14 years.

To all whom it may concern:

Be it known that I, ALFRED C. GILBERT, a citizen of the United States, residing in Hamden, in the county of New Haven and State of Connecticut, have invented a new, original, and ornamental Design for Casing for Fruit-Juice Extractor, of which the following is a specification when taken in connection with the accompanying drawings, of which—

Figure 1 is a front elevational view of a casing for fruit juice extractor showing my new design, Figure 2 is a side elevational view of the same, and Figure 3 is a top plan view.

I claim:

The ornamental design for a casing for fruit juice extractor substantially as shown.

ALFRED C. GILBERT.
